MAGNETOGENERATOR

Edward B. Nowosielski, Sidney, N. Y., assignor to
 Bendix Aviation Corporation, South Bend, Ind.,
 a corporation of Delaware

Application February 26, 1938, Serial No. 192,781

2 Claims. (Cl. 171—209)

The present invention relates to a magnetogenerator and more particularly to a high tension generator adapted to furnish ignition current for internal combustion engines.

It is an object of the present invention to provide a magnetogenerator which is efficient and reliable in operation, simple in construction and easily assembled and adjusted.

It is another object of the invention to provide a magneto that is to be utilized with a two cylinder opposed firing internal combustion engine.

A further object of the invention is to provide a magneto that supplies two high tension sparks simultaneously.

A still further object of the invention is to provide a simultaneous firing magneto that utilizes two separate ignition coils.

Another object of the invention is to provide a double firing magneto having only a single condenser and a single breaker mechanism.

It is another object of the invention to provide a magneto which is incorporated with the internal combustion engine to be ignited and having the rotor of the magneto mounted directly on the shaft of the engine.

A further object of the invention is to provide a magneto in which the induction coils and cores are detachably mounted on the frame of the magneto.

A still further object of the present invention is to provide a flywheel magneto in which the flywheel is readily removable.

The above and further objects and novel features of the invention will more fully appear from the following detailed description taken in connection with the accompanying drawings. One embodiment of the invention has been illustrated in the accompanying drawings, but it is to be expressly understood that the said drawings are for purposes of illustration only and are not to be construed as a definition of the limits of the invention, reference being had primarily to the appended claims for this purpose.

Fig. 1 is substantially a midsectional view through the axis of a magneto illustrating a preferred embodiment of the present invention.

Fig. 2 is a plan view showing the structure of the stator and one embodiment of the rotor.

Fig. 3 is a plan view showing the structure of the stator and another embodiment of the rotor.

Fig. 4 is a sectional view taken substantially on line 4—4 of Fig. 3.

Fig. 5 is a top plan view of the magneto with the flywheel removed.

Referring first to Fig. 1 of the drawings, there is illustrated a magnetogenerator comprising a casing 1 of generally cylindrical shape adapted to be received on the casing of the engine 2 for which the generator is adapted to supply the ignition current. A rotor generally indicated at 3 is rotatably mounted within casing 1 and is mounted on a shaft 4 which may be the shaft of the engine or a stub shaft coupled therewith. A flywheel hub member 5 in the form of a cupped disc having an extended hub 6 is suitably keyed on the end of shaft 4 and is formed at its periphery with a shoulder 7 arranged to substantially enclose the breaker mechanism 8.

Permanent magnets in the form of arcuate bars 11 are arranged in pairs as indicated in Fig. 2 on opposite sides of the axis of the rotor and are arranged to interfit between pole pieces 12 and 13 of suitable magnetic material. Pole pieces 12 and 13 are of unequal angular length for the reasons to be hereinafter more fully explained and are retained in assembled relation with arcuate magnets 11 by means of plates 14 and 15 of suitable non-magnetic material. Suitable rivet means 17 are employed to hold the rotor in assembled relation. Plate 14 has a shoulder 16 which abuts against plate 15 and also is adapted to be placed upon shaft 4 and is held non-rotatably on said shaft by a suitable key means 20. Rotor 3 is held in a locked position on shaft 4 by means of lock nut 18. Tapped holes 19 are placed in shoulder 16 of plate 14 to facilitate the withdrawal of rotor 3 from shaft 4 by means of a suitable tool.

In the embodiment illustrated in Fig. 3 the magnetic circuit of the rotor is strengthened since the length of the arcuate magnets 11' is longer.

As illustrated in Figs. 2 and 3 the inductor circuit is rectangular with laminated inductor elements 21 and 22 having poles 23 and 24 unsymmetrically arranged so that the distance between the poles is greater at one end than it is at the other end. The purpose of this will be set forth more fully hereinafter. Parallel end cores 25 and 26 are detachably mounted on laminations 21 and 22, and adapted to be mounted thereon are ignition coils 27 and 28 shown in Figs. 1 and 3. Clamps 29 securely attach coils 27 and 28 with their respective cores 25 and 26 to inductor elements 21 and 22.

Laminations 23 and 24 are rigidly held together by means of rivets 31 passing through the laminations and being anchored to the top plate 33.

member 32 and to the flanged upper portion of casing 1.

5 Breaker plate 33 is securely mounted by means of screws 36 on the upper end plate 32 and carries the condenser 34, the breaker mechanism 8, cam lubricating means 35 and the conductor supporting means which are fastened to screws 36.

10 Extension 6 of the flywheel hub member 5 also acts as the cam for operating breaker mechanism 8. The cam and flywheel may be removed from shaft 4 very readily simply by loosening nut 37 which will pull the cam and flywheel off shaft 4.

15 The electrical circuit of the magneto is such that the two primary windings of ignition coils 28 and 27 are connected in series with the wire 38 connecting the two primary windings. One end of each of the secondary windings is grounded while the other end of each winding is connected to one of terminals 41 and 42, to which are connected the ignition cables such as 43 leading to the spark plugs of the engine.

20 In the operation of the structure it will be noted that the rotation of the rotor 3 will cause 25 rotor pole shoes 12 and 13 to be presented alternately to stator poles 24 and 23 during each revolution of the rotor so that there will be two reversals of flux for each revolution. When this magneto is used for the ignition of a two cycle 30 twin cylinder engine, the cam 6 and breaker mechanism 8 are so arranged that the primary circuit of the induction coils will be closed during one of the reversals of flux up to the time when the stored primary energy is at its maximum. 35 The breaker mechanism is then opened by the cam, thus allowing a rapid change of flux in the primaries of the coils and thereby generating a high voltage in each secondary of the coils to be used for ignition purposes in the usual manner.

40 According to the present invention, means are provided for quenching the second reversal of flux so that it will not produce a significant amount of voltage in the secondary of the coils.

45 Referring to Fig. 1, it will be seen that this is accomplished by spacing the magnets 11 of the rotor 3 at less than 180 degrees from each other so that the rotor pole shoe 13 subtends an arc considerably greater than the pole shoe 12. The 50 stator pole shoes 23 and 24 are also arranged in substantially the same angular relationship to each other as the magnets 11 whereby in the position illustrated and with the rotor turning in the direction of the arrow a, rotor pole shoe 55 13 is moved out of cooperative relation with stator pole shoe 24 and into such relation with the stator pole shoe 23 at the same time that the rotor pole shoe 12 is being transferred from stator pole shoe 23 to stator pole shoe 24. A 60 rapid reversal of flux through the external magnetic circuit is thus secured, and it is this reversal which is utilized to generate the ignition voltage in the induction coils 27 and 28. When,

however, the rotor has turned through substantially 180 degrees from its position shown in Fig. 1 the reversal of flux will be comparatively gradual since the long rotor pole shoe 13 continues to bridge the short lower gap between 5 stator pole shoes 23 and 24 for a considerable length of time after the rotor pole shoe 12 has left the stator pole shoe 24.

65 Cam 6 is preferably formed as illustrated to maintain the breaker 8 open until after the unused reversal of flux has taken place. This, however, has been found not to be strictly necessary since with the rotor and stator constructed as herein disclosed, the unused reversal of flux is so gradual that it is substantially ineffective 15 to produce undesired impulses in the coil at any normal operating speeds of the device.

70 Although only two embodiments of the invention are illustrated and described, it is to be expressly understood that the same is not limited thereto but that various changes may be made in the design and arrangement of parts illustrated without departing from the spirit and scope of the invention as will now be apparent to those skilled in the art. Reference will be 25 primarily had to the appended claims for a definition of the limits of the invention.

What is claimed is:

1. In a high tension magneto, a two pole magnetic rotor having pole shoes of unequal circumferential extent, a stator comprising two pole shoes which are so spaced circumferentially of the rotor that in one position of the latter said stator pole shoes bridge the spaces between said rotor pole shoes and two ignition coils having 35 primary and secondary windings wound on metallic cores which join adjacent ends of said stator pole shoes on opposite sides of said rotor, the primary windings of said coils being connected in series and the secondary windings 40 thereof being independent of each other, and a single circuit breaker mechanism for periodically interrupting the circuit containing said primary windings.

2. In a high tension magneto, a two pole magnetic rotor having pole shoes of unequal circumferential extent, a stator comprising a pair of pole pieces having pole shoes of substantially equal angular extent and separated circumferentially of the rotor by unequal spaces which 50 correspond approximately to the angular extent of said unequal rotor pole shoes, the latter being adapted to bridge said spaces when the rotor is in one angular position, metallic cores joining adjacent ends of said pole pieces on opposite sides of said rotor and an ignition coil on each of said cores having primary and secondary windings, the primary windings of said coils being connected in series and the secondary windings thereof being independent of each other, and 60 a single circuit breaker means for interrupting the circuit containing said primary windings.

EDWARD B. NOWOSIELSKI.
